(57) **CLAIM**

The ornamental design for a phone case as shown and described.

DESCRIPTION

FIG. 1 is a front, left-side, and top perspective view of a phone case showing my new design;

FIG. 2 is a rear, right-side, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and

FIG. 9 is an enlarged detail view of the corresponding encircled region 9 of FIG. 1; and,

FIG. 10 is an enlarged detail view of the corresponding encircled region 10 of FIG. 1.

The dashed broken lines in the drawing figures form no part of the claimed design and depict portions of the phone case that form no part of the claimed design. The dot-dash broken lines in FIGS. 1, 9, and 10 form no part of the claimed design; they delineate portions of the phone case that are part of the claimed design and that are shown on an enlarged scale in FIGS. 9 and 10.
